UNITED STATES PATENT OFFICE.

ROY BATES, OF NEVADA, MISSOURI.

CHECK PERFORATOR.

Application filed January 31, 1922. Serial No. 533,080.

To all whom it may concern:

Be it known that I, ROY BATES, a citizen of the United States, and a resident of Nevada, in the county of Vernon and State of Missouri, have invented a new and Improved Check Perforator, of which the following is a description.

My invention relates to a check protecting means and particularly to a device for perforating the check.

The general object of the invention is to provide a simple device that may be employed with facility to quickly perforate the check following the lines of the letters and numerals in the amount for which the check is drawn.

The nature of the invention and its distinctive features and advantages will clearly appear as the description proceeds.

Reference is to be had to the accompanying drawings forming a part of this specification, it being understood that the drawings are merely illustrative of one example of the invention.

Figure 1 is a side elevation of a check perforator embodying my invention;

Figure 2 is a plan view thereof;

Figures 3 and 4 are cross sections on the lines 3—3, 4—4, of Figure 1.

In carrying out my invention in accordance with the illustrated example, the perforating device is made with a coil 10 from which the upper and lower arms 11, 12 extend. A tie 13 is provided to limit the flexure of the arms 11 and 12 relatively to each other, said tie being in the form of a loop, the sides of which cross at the center as clearly shown in Figure 3. The forward end of the upper arm 11 is downturned to provide a perforating member 14, which terminates in a puncturing point 15 bevelled to punch from a check A a minute part as indicated in exaggerated form at *a*, Figure 4. The forward end of the lower arm 12 is formed with an upstanding member 16 at the front end which is disposed rearward of the downturned member 14 and on which upstanding member 16 is secured or formed a small table 17 extending forwardly beneath the downturned perforating member 14 and formed with a hole 18 alining with said perforating member.

With the described arrangement the perforating device is taken in hand and the check is placed on the table 17, the check being turned and manipulated to bring successive portions of the lines of a letter or number beneath the perforating member 14 and the arms 11 and 12 are pressed toward each other to cause the member 14 to puncture the check, the punched out portion *a* dropping from the under side of the table.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A perforating device of the class described formed of wire and having a spring coil therein and presenting arms extending forwardly from said coil, the one arm having a downturned puncturing member at the front end thereof, and the other arm supporting a table extending beneath the puncturing member and formed with a hole in register with said puncturing member.

2. A perforating device of the class described formed of wire and having a spring coil therein and presenting arms extending forwardly from said coil, the one arm having a downturned puncturing member at the front end thereof, and the other arm supporting a table extending beneath the puncturing member and formed with a hole in register with said puncturing member; together with a tie extending about the arms adjacent to said spring, the sides of the tie crossing.

3. A perforating device of the class described, including arms movable toward or from each other, the one arm having a downturned puncturing member, the lower end of which is bevelled, the other arm having an upstanding member, and a table on the upstanding member extending beneath the downturned member, said table having a hole in alinement with the downturned member.

ROY BATES.
